UNITED STATES PATENT OFFICE.

SVENING HILMER SVENSSON AND KARL OSKAR ENGVIST, OF BOFORS, SWEDEN, AS
SIGNORS TO AKTIEBOLAGET BOFORS, OF BOFORS, SWEDEN.

CENTERING AND LOCKING MEANS FOR THE PUNCHES IN RIVET AND FORGING MACHINES.

Application filed May 8, 1923. Serial No. 637,604.

To all whom it may concern:

Be it known that we, SVENING HILMER SVENSSON and KARL OSKAR ENGVIST, subjects of the King of Sweden, both residing at Bofors, Sweden, have invented certain new and useful Improvements in Centering and Locking Means for the Punches in Rivet and Forging Machines, of which the following is a specification.

10 The present invention relates to a unique construction of the centering and locking means for the punches in rivet and forging machines provided with two or more punches.

15 The centering devices as heretofore known and used suffer from the inconvenience of the working pressure loading the punch shifting device, either wholly or partly, whereby the latter will be subjected to heavy wear. Other known centering devices in use which are not hampered by this drawback command a limited space owing to their being mounted in the main slide proper, and on account of this some of the 20 parts will be weak, while the centering screws are rendered difficult of access. As distinguished from these known arrangements, the present invention is so devised that the various parts may be amply dimensioned, besides which the parts constituting the lock are entirely visible and allow of ready adjustment in the run of the machine.

25 The invention is illustrated on the accompanying drawings. Fig. 1 is a lateral view, with certain parts shown in section, of an entire machine having three punches, and provided with means constructed according to the present invention. Fig. 2 is a lateral view of a detail of the arrangement as applied to a machine with two punches. Fig. 3 is a plan view of the machine. Fig. 4 is a section on line 4—4 in Fig. 3. Fig. 5 shows a modification in longitudinal section, and Fig. 6 is an end view of the said modification.

30 5 designates the crank shaft or main shaft of the machine the crank of which is connected in known manner with the main slide 7 by means of the connecting rod 6, the main slide 7 being movable in the longitudinal direction of the machine. The lateral guides of the slide belonging to the frame proper are denoted by 31 (Fig. 4). At the bottom the slide bears on the slide bars 34 which, in

turn, rest on ledges provided on the guides 31 and at the top the slide is guided by the overlapping bars 35 attached to the lateral guides 31.

35 Provided in the horizontally movable main slide 7 is a slide 8 adapted to be moved vertically, the said slide 8 carrying punches 1, 2 and 3 arranged beneath each other. This punch slide 8 is guided by the vertical guides 29 and 30 (Figs. 3 and 4 which, preferably, are made of phosphor bronze. 65

40 Arranged on the slide 8 beneath each other are two wedge-like projections 13 of hardened steel forming between them a V-shaped slot. The position and the shape of these projections is adapted to the distance 70 between the center lines of the punches and to the wedge-shaped end of the lock bolt 15, which will be described hereinbelow.

45 Provided in the part 40 of the machine frame, opposite the punches, is a bore hole 41 having an inclination of about 10° to the horizontal plane, and fitted in this bore hole is a bolt housing 14. This bolt housing is in turn provided with a bore hole parallel to the horizontal plane, in which latter bore hole the lock bolt 15 is fitted so as to be movable therein. This bolt will thus form an angle of 10° with the line of symmetry of the bolt housing, and it is parallel to the path of movement of the main slide 7. The 50 lock bolt 15 is actuated by an adjustable spring 16 tending to press the same against the punch slide 8. By means of the screw 19 the bolt housing 14 may be displaced in its longitudinal direction relatively to the frame, whereby the bolt 15 is evidently raised or lowered. By suitable means such as a locking screw the bolt housing 14 is 55 locked in the frame in the desired position. 90

60 The die mounted in the frame portion 40 and wherein the blank to be treated, such as a screw blank 42, is held in a fixed position opposite the slide 8, is designated by 43. 95

65 The movements of the slide 8 are step-wise according to the distance between the punches and the action thereof. 100

70 At the beginning of the working operation the punch 1 and the center line of the die should be in alignment, that is to say the punch should be on the level indicated by 105 the chain-dotted lines 37 in Fig. 4.

75 The first step in the upsetting operation on the blank is then performed. During the

following revolution of the shaft 5, the slide 8 is raised to the position shown in the drawing, that is to say so much that the center line of the punch 2 is brought in alignment with the center line of the blank and the die, and during the next following revolution of the shaft 5 the slide 8 will be further raised so that the punch 3 is brought in alignment with the blank 42 in the die 43. During the third revolution of the shaft 5, when the ready screw blank is ejected and another blank is fed forth, the slide 8 will be brought down by one stroke to the initial position, so that the punch 1 will again assume its centered position, that is to say be brought in alignment with the blank, the operation described being then repeated.

These movements of the slide 8 are effected by a punch shifting mechanism operating in the following manner. Mounted on a secondary shaft 22 (Figs. 1 and 4) which, in a machine with three punches, has a speed equal to one third of the speed of the crank shaft 5, is a cam disk 20 provided with a slot 21. Mounted on a fork 25, which is guided by a die block 23 on the shaft 22, is a roller 24 engaging the slot 21 of the said cam disk 20. The motion thus imparted to the fork by the rotation of the shaft 22 is transmitted through a pivot 26 to a lever 27, and further through a shaft 32 and a lever 43 to a roller 12 mounted on a stud, said roller 12 running between guides 11 on the slide 8. The cam disk 20 imparts a constant unvarying motion to the fork 25, but the position and the movements of the punch slide 8 may be varied by altering the lengths of the levers by displacing the pivot 26 and the stud of the roller 12 through the medium of screws 28 and 33. This punch shifting mechanism is substantially of the same construction as used in certain known machines of the type to which the present invention refers.

When the slide 8 of the shifting mechanism is moved downwards, so that the punch 1 is brought in alignment with the die, the lower end of the adjusting screw 10 is caused to bear on the upper side of the main slide 7. The screw is now adjusted (if it does not already occupy a fully adjusted position) so that the center lines of the punch 1 and the die will be situated on exactly the same straight line. When the main slide 7, and thus also the slide 8 together with the punch, are now moving downwardly in a direction toward the die, the oblique upper side of the upper lock projection 13 will hit the lower side of the correspondingly shaped oblique lower face of the outer end of the lock bolt, whereby the slide 8 will be securely jammed (locked) against the screw 10. The distance between the said projection 13 and the lock bolt 15

is so adapted that the said locking of the slide 8 will take place before the punch starts working on the blank in the die. On the continued motion of the slide 7 in a direction toward the die, the lock bolt 15 will be displaced into the housing, thereby compressing the spring 16, the pressure of which against the bolt will then keep the slide 8 securely locked during the upsetting of the screw blank. When the slide 7 moves away from the die, the bolt 15 will evidently return to its initial position under the influence of the spring pressure.

During the next revolution of the main shaft of the machine, the punch 2 has to be locked in alignment with the blank in the die, that is to say the shifting mechanism will displace the slide 8 during this revolution in such a manner that the punch 2 is brought into the working position. When the main slide is moving during this revolution toward the die, the locking bolt will be engaged between the two projections 13, before the punch starts working on the blank, the slide 8 being thus adjusted and locked by the locking bolt in the exact position in which the punch is accurately centered with respect to the die. The adjustment of the locking bolt, so that it will accurately center the other punch, is effected by a displacement of the bolt housing 14, in that the bolt 15 will then be raised or lowered, whereby corresponding raising and lowering of the slide 8 is taking place when the locking bolt 15 is engaged between the projections.

This adjustment will have no influence on the centering of the two other punches, such adjustment only altering the length of the distance along which the oblique surfaces of the locking bolt 15 and the projections 13 slide on each other.

During the third revolution of the shaft, when the slide of the shifting mechanism is raised so as to bring the punch 3 in alignment with the die, the bottom surface of the lower projection 13 will, on the movement of the main slide 7 in a direction toward the die, be caused to co-operate with the upper oblique surface of the locking bolt 15, whereby the slide 8 will be pressed against the nut 9 which is mounted on a rod 50 attached to the main slide 7 and extending freely through a bore hole in the slide 8. By adjusting this nut, the locking of the punch 3 may thus be effected in an absolutely proper position relatively to the die.

The punch shifting mechanism can and must be so adapted that there will be a clearance of about 2 millimeters for the slide 8 at the extreme positions for the different adjustments of the level, so that the very last step of the movement into the extreme position is effected by the co-operation of the wedge-shaped locking parts, whereby the

pressure from the shifting mechanism is entirely relieved, and an adjustment may be effected through the nut 9 and the screws 10 and 19 during the run of the machine, 5 irrespective of the shifting mechanism.

When using only two punches (Fig. 2), a cam disk is evidently employed, in place of the three-step cam disk 20 used in the embodiment according to Fig. 1, which will 10 only adjust the slide on two different levels corresponding to the positions of the punches 1 and 2 in Fig. 2. The locking of the slide 8 on a level corresponding to the working position of the punch 1 is effected by a 15 co-operation between the top side of the single projection 13 and the bottom side of the wedge-shaped end of the locking bolt, the slide 8 being thus pressed against the screw 10, and the locking of the punch 20 2 in alignment with the die is effected by a co-operation between the top side of the locking bolt and the bottom side of the projection 13, the slide 8 being thus pressed against the nut 9.

It is also possible, when punching with only two punches, to use the slide and the projections shown in Fig. 1, only the three-step cam disk 20 is replaced by a two-step cam disk.

The locking bolt 15 is formed at its rear end into a boss 49 preventing the bolt from rotating, and an offset 18 on the boss serves as an abutment against a rawhide packing 17, so that no beats will be heard against 35 the bolt housing in machines running at a high rate of speed.

Figs. 5 and 6 show a modification of the arrangement of the locking bolt 15 and the bolt housing 14.

According to this modification, the locking bolt is inserted in a bore hole in the frame 40, which bore hole is parallel to the direction of movement of the main slide 7, and the locking bolt is mounted eccentrically 45 in the bolt housing 14, so that the bolt 15 may be raised or lowered by rotating the said housing.

If desired, the projection or projections 13 may be vertically adjustable instead of 50 the bolt 15.

It is also within the scope of the invention to arrange the bolt on the slide 8 and the projections on the portion of the frame opposite the slide, but such an arrangement 55 is believed to be less practical.

What we claim as new and desire to secure by Letters Patent of the United States of America is:—

1. In punching machines the combination 60 of a slide, a number of punches mounted on the slide a gate carrying the slide for reciprocating the same in the punching direction, a die for the blank to be punched, a shifting mechanism for giving the slide such an intermittent motion so that the punches in

their proper turns are brought in alignment with the die, means for accurately adjusting and locking the slide in each separate punching position, said means consisting of two lock members, one of these members 70 consisting of a bolt, a housing which does not take part in the adjusting movement of the slide, said bolt being adjustably fitted in said housing so as to be pressed inwardly in this latter when the slide is moved towards the die, the other lock member being mounted on the slide and means, whereby the lock members are brought out of engagement with each other automatically, only on account of the movement of the gate with the 80 slide rearwardly to a certain degree.

2. In punching machines the combination of a slide, a number of punches mounted on the slide, a gate carrying the slide for reciprocating the same in the punching direction, a die for the blank to be punched, a housing for the die provided with a hole, a shifting mechanism for giving the slide such an intermittent motion so that the punches in their proper turns are brought in alignment with the die, means for accurately adjusting and locking the slide in each separate punching position, said means consisting of two lock members, one of these members 90 consisting of a bolt, a housing which does not take part in the adjusting movement of the slide, said bolt being adjustably fitted in said housing so as to be pressed inwardly in this latter when the slide is moved towards the die, the other lock member being 95 mounted on the slide and the bolt housing being fitted in the hole of the die housing, said hole having an oblique direction with respect to the direction of the punching operation, whereas the locking bolt is mounted in parallel to the direction of the punching operation so that, on the bolt housing being displaced in the said bore hole, the locking bolt will be adjusted at right angles 100 to the punching direction.

3. In punching machines the combination of a slide, a number of punches mounted on the slide, a gate carrying the slide for reciprocating the same in the punching direction, a die for the blank to be punched, a housing for the die provided with a hole, a shifting mechanism for giving the slide such an intermittent motion so that the punches in their proper turns are brought in alignment with the die, means for accurately adjusting and locking the slide in each separate punching position, said means consisting of two lock members, one of these members 110 consisting of a bolt, another housing, which does not take part in the adjusting movement of the slide, said bolt being adjustably fitted in said latter housing so as to be pressed inwardly in this housing when the slide is moved towards the die, the other lock member being mounted on 115 120 125 130

the slide and means, whereby the lock members are brought out of engagement with each other automatically, only on account of the movement of the gate with the slide rearwardly to a certain degree, the bolt housing being fitted in the hole of the die housing, said hole having an oblique direction with respect to the direction of the punching operation, whereas the locking

bolt is mounted in parallel direction of the punching operation so that, on the bolt housing being displaced in the said hole, the locking bolt will be adjusted at right angles to the punching direction.

In testimony whereof we affix our signatures.

SVENING HILMER SVENSSON.
KARL OSKAR ENGKVIST.
